Inventor

Sigurd O. Berven

SIGURD O. BERVEN, OF SEATTLE, WASHINGTON.

BATHTUB.

Application filed July 7, 1923. Serial No. 573,254.

To all whom it may concern:

Be it known that I, SIGURD O. BERVEN, a citizen of Norway, residing at Seattle, in the county of King and State of Washington, have invented certain new and useful Improvements in Bathtubs, of which the following is a specification.

This invention relates to improvements in bath tubs.

10 The prime object of this invention is to provide a bath tub with means to permit the mixing of the hot and cold water before same enters the body of the tub and to permit the mixed water to enter the body of the 15 tub at various parts around the rim of same.

A further object of the invention is to provide a bath tub of the above indicated character that is provided with means 20 formed in the rim of the tub to permit the occupant of the tub to receive a shower bath.

A still further object of the invention is to provide a bath tub with means formed 25 in the rim of same to permit a fine stream of water to flow down the sides of the tub while the tub is being used and after using same to prevent scum, or other substance from adhering to the sides of the tub.

30 An additional object of the invention is to provide means associated with a bath tub that will prevent scum and other dirt from accumulating on the sides of the tub and will eliminate the difficult and disagreeable task of washing out the tub after using 35 same.

These and like objects of the invention will be better understood as the description 40 proceeds and as is specifically pointed out in the appended claims.

Referring to the accompanying drawing in detail, which forms a part of this specification,

45 Figure 1 is a vertical longitudinal section of a bath tub constructed in accordance with my invention.

Figure 2 is a section taken on line 2—2 of Figure 1.

50 Figure 3 is a fragmentary section through the rim of a tub showing a modified form.

Figure 4 is a similar view showing a further modified form, and

55 Figure 5 is a similar view showing a still further modified form.

Referring to the drawing in detail, like 55 characters will be used to designate like parts in the different views.

In the drawing, the numeral 1 indicates the body of a tub, which can be of any desired construction and shape, 2 the rim, 60 3 the supporting base, 4 the drain positioned in the bottom of the tub, and 5 the water inlet pipes, one of which is cold water and the other hot water.

The rear end of the tub 1 or the part adjacent the inlet pipes is provided with a mixing chamber 6, which communicates with the hot and cold water pipes. The mixing chamber 6 is partly covered by the flange 7 which extends all the way around the tub, 65 as is clearly indicated in Figure 1. After the hot and cold water have been thoroughly mixed in the chamber 6, the water passes up into the rim 2 and the force of the water entering the mixing chamber 6 forces the water around the flange 7 all the way around the rim of the tub, and allows same to enter the body 1 through a series of openings 8 formed between the rim 2 and the walls 70 of the tub.

In Figure 3, I have shown a slightly modified form, wherein the flange 7 of the tub is so shaped as at 9 to permit a certain amount of water to remain on the flange, thus heating or cooling the rim 2 as the 75 case may be.

In Figure 4, I have shown a modified form, wherein the flange 7 is so formed as at 10 to compel all the water held on same to be discharged into the tub.

In Figure 5, I have shown a still further modified form, wherein the rim 2 is formed with a partition 11, so that while hot and cold water may be mixed and forced around in the compartment 12 and discharged through the openings 8, hot or cold water can also be forced into the compartment 13, and discharged out of the openings 14 to permit the taking of a shower bath.

100 In order to permit the cleaning out of the mixing chamber 6, a screw threaded plug 15 is positioned therein, which can be readily removed.

105 From the foregoing description of my invention taken in connection with the accompanying drawing, it can be readily seen that I have provided an improved bath tub,

which is durable, efficient for the purpose intended, and one that can be manufactured and installed at a relatively low cost.

While I have shown and described the 5 preferred forms of my invention, I realize that various minor changes may be resorted to, without departing from the spirit and scope of the invention as claimed, and therefore, I do not wish to limit myself to the 10 exact details of construction shown, nor to the combination and arrangement of parts.

In view of the foregoing description of my invention taken in connection with the accompanying drawing, it is thought that 15 any further explanation as to the construction and objects of the invention are unnecessary. However, I wish to have it understood that while I have only shown my invention applied to a bath tub, same can be 20 used for sinks, wash tubs, wash basins, and similar vessels, and soap may be mixed with the water so as to make the cleaning agent more efficient.

What I claim as new and desire to secure 25 by Letters Patent is:

1. A device of the character described comprising a receptacle, a passageway formed around the upper edge of the receptacle and communicating therewith, a mixing 30 chamber formed at the forward portion of the passageway below the same, said mixing chamber having communication with the passageway in its top wall so that said chamber will be filled before the water can enter 35 the passageway, and means for connecting hot and cold water pipes to the mixing chamber.

2. A device of the character described comprising a receptacle, a passageway 40 formed around the upper edge of the receptacle, a mixing chamber formed at the forward portion of the passageway below the same, a baffle plate attached to one of the side walls of the mixing chamber and ex- 45 tending partially across the top thereof be-

tween the passageway and the same, and means for connecting hot and cold water pipes to the mixing chamber.

3. A device of the character described comprising a receptacle, a passageway 50 formed around the upper edge of the receptacle and communicating therewith, a mixing chamber formed at the forward portion of the passageway below the same, said mixing chamber having communication with the passageway in its top wall so that said chamber will be filled before the water can enter 55 the passageway, means for connecting hot and cold water pipes to the mixing chamber, and means for draining said mixing chamber. 60

4. A device of the character described comprising a receptacle, a passageway formed around the upper edge of the receptacle, a mixing chamber formed at the forward portion of the passageway below the same, a baffle plate attached to one of the side walls of the mixing chamber and extending partially across the top thereof between the passageway and the same, and hot 65 and cold water pipes connected to said mixing chamber on the opposite side from which said baffle plate extends. 70

5. The combination with a receptacle of a passageway having two rows or series of 75 apertures at its lower side communicating with said receptacle, a partition separating the two rows of apertures to form two passageways, a mixing chamber formed at the forward part of the rim communicating 80 with the passageways, and means for supplying hot and cold water into said mixing chamber. 85

In testimony whereof, I have affixed my signature in the presence of two witnesses.

SIGURD O. BERVEN.
